UNITED STATES PATENT OFFICE

BERNARD F. LUNDELL, OF WELCH, MINNESOTA

DISHWASHING MACHINE

Application filed April 24, 1928. Serial No. 272,490.

This invention relates generally to washing machines and pertains particularly to a machine for washing dishes, silverware and the like.

5 The primary object of this invention is to provide, in a manner as hereinafter set forth, a machine designed to receive plates, cups, saucers, bowls, and silverware and to scrub the same thoroughly, maintaining each 10 article, with the exception of the silverware, in position for the action of a scrubbing device.

Another object of the invention is to provide, in a manner as hereinafter set forth, 15 a dishwashing machine having individual brushes for each article of chinaware or like receptacles, by means of which the said receptacles are thoroughly scrubbed.

A still further object of this invention is 20 to provide, in a manner as hereinafter set forth, a dishwashing machine in which the various articles to be cleansed are positioned in individual receptacles or compartments to be operated upon by a cleaning element 25 in the compartment, means being provided for the simultaneous operation of the cleaning elements and also for the simultaneous draining of the compartments.

The invention will be best understood 30 from a consideration of the following detailed description taken in connection with the accompanying drawings forming a part of the present invention with the understanding, however, that the invention is not 35 confined to any strict conformity with the showing of the drawings but may be changed or modified so long as such changes or modifications mark no material departure from the salient features of the invention 40 as expressed in the appended claims.

In the drawings:

Figure 1 shows the machine embodying the present invention, in side elevation.

Figure 2 is a top plan view of the machine.

Figure 3 is an enlarged horizontal section of the machine taken substantially upon the line 3—3 of Figure 1.

Figure 4 is a vertical longitudinal section 50 taken upon the line 4—4 of Figure 2.

Figure 5 is a vertical longitudinal section taken upon the line 5—5 of Figure 3.

Figure 6 is a transverse section taken upon the line 6—6 of Figure 3.

Figure 7 is a longitudinal section taken 55 upon the line 7—7 of Figure 3.

Figure 8 is a horizontal section taken transversely of one end of the machine.

Figure 9 is a view in end elevation of the end of the machine upon which the operating mechanism is mounted.

Figure 10 is a bottom plan view of the outer one of a pair of the cup or bowl brushes.

Figure 11 is a vertical sectional view 65 through a pair of plate scrubbers.

Figure 12 is a sectional view taken substantially upon the line 12—12 of Figure 11.

Figure 13 is a vertical sectional view 70 through one of the cup or bowl scrubbers.

Figure 14 is a sectional view taken horizontally of the structure shown in Figure 13, substantially upon the line 14—14 of Figure 13.

Referring now to the drawings in detail 75 wherein like numerals of reference indicate corresponding parts throughout the several views, the numeral 1 indicates generally the dishwashing machine body. As shown the body is generally of broad and relatively 80 shallow construction and has the top edges connected by the transverse and longitudinal division bars 2 and 3 respectively thus forming four top openings each of which is covered by a door 4 hingedly attached to the adjacent side wall of the body, as indicated by the numerals 5.

Within the top of the body 1 beneath and in close proximity to the doors 4 is a horizontal partition wall 6 which extends over 90 the entire area of the body.

Adjacent one side wall of the body beneath the partition there is arranged a longitudinally extending series of pairs of plate washers each of which plate washers is indicated as a whole by the numeral 7. The washers 7 of each pair are arranged in spaced relation longitudinally of the body 1 and each washer comprises a vertically arranged narrow rectangular receptacle 8 which opens 100

upwardly through the partition wall 6. The receptacles may be formed at the top edges of the walls integral with the wall 6, if desired, as shown in Figure 11 of the drawings. 5 As is also shown in this figure the partition wall 6 between each pair of receptacles is provided with a longitudinally extending slot 9 and the opposing walls of the receptacles forming each pair are provided with 10 vertical recesses or slots 10 each of which opens into the slot 9 and has a shaft bearing 11 formed at the lower end thereof, or in other words at approximately the central portion of the inner wall of the receptacle 8. 15 The lower wall of each receptacle 8 is in the form of a basin 12 and opens at its central portion into a valve casing 13 in which is rotatably positioned a cylindrical valve body 14 which is provided with a 20 transverse passageway 15. The valve casing 13 opens downwardly into the drain pocket 16, one end of which pocket has connected thereto the laterally extending drain pipe 17 which discharges into a main drain-off 25 pipe 18 that runs longitudinally of the machine.

Each valve body 14 has a rod extending from one end thereof as indicated at 19, which rod carries upon its free end the crank 30. The cranks 20 are all connected for simultaneous actuation by a control bar 21 which runs longitudinally of the machine, one end of the bar being supported in any suitable manner to permit of its being reciprocated while the opposite end thereof is pivotally attached to a vertically mounted control lever 22, the lower end of this lever being mounted upon a suitable bracket 23 and having its upper end positioned adjacent 35 an opening 24 formed in the partition wall 6, through which it is accessible. From the description thus far given it will be readily understood that the contents of all of the receptacles 8 can be readily drained off 40 through the oscillation of the lever 22 in the desired direction to simultaneously open the valves through the rotation of the bodies 14.

Mounted upon the floor 25 of the bodies 15 to extend upwardly between each pair of receptacles 8 is a pair of spaced substantially A-shaped standards 26 each of which is provided at its top with a bearing 27 and at its intermediate portion with the bearing 28. 55 All of the bearings 27 and 28 are in alignment longitudinally of the machine, the bearings 28 being located in a plane a substantial distance below the receptacles 8.

Extending longitudinally of the machine 60 through the bearings 28 is a crank shaft 29 carrying a crank 30 for and arranged between the standards 26 of each pair, as shown in Figure 11.

Mounted between the bearings 27 of each 65 pair of standards is an upper crank 31 hav-

ing the laterally extending aligned hubs 32 each projecting through the bearing 27 in the manner shown. Each of these hubs 32 receives a stub shaft 33 which extends through and is supported in the adjacent 70 receptacle wall bearing 11. Each of the stub shafts 33 carries upon its inner end, within the receptacle into which it extends the circular brush back 34 which has projecting from the face thereof the brush 75 bristles 35.

Within each receptacle 8 there is mounted in the brackets 36 the ends 37 of a split wire ring 38 which forms a dish supporting bracket, a portion of this ring body 38 being extended inwardly as at 39 and formed to set up the centrally positioned ring 40 which carries a cushion pad 41 designed to bear against the back of a dish when the same is placed in the receptacle to rest upon the dish edge engaging portions 42 of the wire rings. As is shown the wire ring and pad 41 faces the brush bristles 35 so that the face of a plate will be held by the ring and pad against the bristles. 90

The cranks 30 of the shaft 29 are connected to the upper cranks 31 which are in overlying relation thereto by the connecting rods 43.

It is preferred in the construction of this 95 machine that there be provided twelve pairs of plate washers 7 thus making the machine capable of handling twenty-four plates at one operation.

The shaft 29 is supported in suitable 100 bearings 44 at each end of the machine and at one end is provided with an extra crank 45 which is designed to be connected through the medium of the connecting rod 46 with the drive shaft hereinafter described. 105

Extending longitudinally within the body of the machine adjacent the plate washers described is a series of cup washers each of which is indicated as a whole by the numerical 110 47. Each of the cup washing structures comprises a cylindrical receptacle 48 having the depressed bottom 49 through the central portion of which a packed bearing 50 is formed. Each of these receptacles 115 48 opens at the top through the partition wall 6 and may be formed about its top edge integral with this wall.

Upon the floor of the body directly beneath the center of each receptacle is a thrust bearing 51 in which is mounted one end of a vertical shaft 52 which extends upwardly through the spaced bearing 50 and terminates at a point adjacent the top of, and within, the receptacle 48. 120

Each of the shafts 52 carries below the overlying receptacle a gear 53 and just above the gear the shaft extends through a bearing 54 which is carried upon a bearing supporting bar 55 that extends longitudi- 125 130

nally of the machine body. At its upper end within the associate receptacle 48 each shaft carries a collar 56 which in turn supports a resilient pad 57.

Surrounding the collar 56 which is mounted upon the upper end of the shaft 52 is a brush collar 58 from which there extends a series of outwardly and downwardly curving resilient arms 59 carrying brush bristles 60. These arms at their lower ends turn inwardly and are provided with the slotted terminals 61 which lie transversely of the shaft and have extended therethrough securing screws 62 which are carried by the shaft.

The resilient arms 59 may be of course of any desired construction but it is preferred that they be of twisted wire having the bristles 60 clamped between the twisted strands of the wires in the usual manner.

Each of the cup washing receptacles is provided with a cover or lid 63, which may be hingedly attached to the partition wall 6 or otherwise suitably connected therewith.

Upon the under face of each cover 63 and at the central portion of the same there is attached thereto by the rivet or screw member 64 the resilient button 65 which, when the lid is closed comes into close relation with the resilient body 57 or contacts with the same.

This rubber button 65 carries a radially extending series of downwardly curving resilient arms 66 each of which carries throughout its length the bristles 67 which oppose the bristles 60 of the arms 59. The arms 56 preferably describe the same arc as the arms 59 and the bristles of the two sets of arms are in slightly spaced relation as shown in Figure 13.

At the lowest point in the depressed bottom 49 of each receptacle a valve shell 68 is formed which has communication with the interior of the receptacle and with a pocket 69 which, like the pocket 16 of the plate washing receptacles, communicates with a suitable drain pipe 70.

Within each valve shell 68 a rotary valve cylinder 71 is positioned which has a passage 72 therein through which communication can be established between the receptacle and the drain pipe to permit the running off of the liquid contents thereof.

The actuation of the valve cylinders is accomplished through the use of a common control bar 73 which extends throughout the length of the machine body and is connected with crank elements 74 carried by a shaft 75 projecting from each valve cylinder. As in the case of the control shaft 21 for the valve cylinders 14, the bar 73 may be mounted at one end in any suitable manner to permit reciprocatory motion while the opposite end is pivotally connected to a lever 76 pivotally mounted upon a bracket 77 carried by

one end of the wall of the machine. This lever 76, like the lever 22 extends upwardly toward an opening 78 formed in the partition wall 6 through which the operator of the machine can reach the lever.

Extending longitudinally of the machine beneath the receptacles 48 is a drive shaft 79 each end being mounted in suitable bearings 80 upon the end walls of the structure. At the end of the machine where the control levers 22 and 26 are located the shaft 79 extends through the end wall and carries upon its outer end the gear 81. This gear 81 is in mesh with a relatively large gear 82 which is also located exteriorly of the machine and is mounted upon the extended end of a third longitudinally extending shaft 83 which is within the body of the machine. The shaft 83 is mounted, like the shafts 29 and 79, in bearings 84 carried upon the end walls of the body. The gear 82 is provided with suitable means for effecting its rotation manually as for example by the provision of a handle 85. It is of course to be understood that a mechanical means may be employed for operating these gears, if practicable.

The shaft 79 is provided adjacent the working end of the machine with a large crank 86 to which is connected the crank arm 46 and a crank arm 87, the arm 87 having connection at its other end with the crank 88 of the shaft 83.

The shaft 79 carries a plurality of worms 89, one for each of the gears 53. In this manner upon the rotation of the shaft 79 the shaft 29 will be rotated and simultaneous operation of the cleaning devices in the receptacles 8 and 48 will be effected.

The central portion of the bottom 25 of the machine is provided with a longitudinally extending gutter 90 which gradually deepens toward one end of the machine and terminates in the outlet 91 which is normally closed by the plug 92. The drain pipes 110 18 and 70 discharge into this gutter as clearly shown in Figures 5 and 7.

The receptacles 8 and 48 take up substantially half of the machine as is clearly shown in Figure 3. The other half of the machine is provided with bowl washers each of which is indicated as a whole by the numeral 93. Each of these bowl washers is of exactly the same structure as the cup washers 47 except that they are slightly larger.

The vertical shafts 94 which are mounted at their lower ends in the thrust bearings 95, are operated through the medium of a worm and gear structure indicated as a whole by the numeral 96, as in the case of the cup washers. The worm of this structure is carried upon a fourth shaft 97 which extends longitudinally like the other shafts 130

and carries a crank 98 at the working end of the machine which crank may be connected to the shaft 79 in the same manner in which the shafts 29 and 83 are connected thereto, that is through the medium of the connecting rod 99.

The same type of drain means is employed for the bowl washers 93, as is employed for the cup washers, and these drains are controlled by the bar 100 which extends beneath the bowl washers and is designed for reciprocatory motion, one end being suitably attached to the standard 101 which extends from the cross bar 2 to the floor 25.

15. The other end of the bar 100 is pivotally attached to the lever 102 which is mounted upon the bracket 103 in turn mounted upon the end wall of the body remote from the wall upon which the levers 22 and 26 are mounted. This lever is accessible through the opening 104 which is formed through the partition 6.

A drain pipe 105 extends longitudinally of the machine beneath the bowl washers 93 and is connected therewith in the same manner in which the drain pipes 18 and 79 connect with the receptacles 8 and 48 and discharges into the gutter 90 like them.

30. In alignment with the bowl washers 93 there is arranged an elongated rectangular opening 106 formed through the partition wall 6 (see Fig. 6) and bordered on three sides by the depending apron walls 107 and 108, the walls 107 being at each end of the opening whereas the wall 108 is at the inner side, the longitudinal side wall of the machine body constituting the other side wall of the opening.

Each end wall apron 107 has an inwardly 40. extending flange 109 at the lower edge thereof and upon these flanges there rests the elongated rectangular silver receptacle 110, the receptacle being surrounded by the apron walls and below the partition wall 6.

45. The silver receptacle 110 is of materially less width than the space between the side apron wall 108 and the adjacent side wall of the apron body and is designed to be reciprocated transversely of the machine.

50. This reciprocatory motion is obtained through the connection with the ears 111 upon the bottom of the receptacle 110 of crank arms 112 which are connected with cranks 113 carried by the shaft 83.

55. The silver receptacle 110 has a drain gutter 114 formed longitudinally of the bottom thereof the deepest point of which gutter is at the central portion of the receptacle body. A suitable drain plug 115 is removably positioned in this gutter, by means of which the contents of the receptacle can be run off when desired.

60. The cover door 4 which overlies the silver washing receptacle has secured to its under-

70. face a plurality of scrubbing brushes 116, which when the cover door is in position project into the silver receptacle to a point in close proximity to the bottom thereof. It will be readily understood that when 70 water is placed in the receptacle 110, the silver placed therein and the cover door closed, the reciprocation of the receptacle through the medium of the connecting rod 112 actuated by the rotating crank 113, will 75 cause the brushes to scrub the silver and thus thoroughly clean the same.

From the foregoing description it will be readily seen that a large number of dishes and a large quantity of silverware can be 80 thoroughly scrubbed at one operation.

85. The brushes 116 are preferably arranged in groups which extend transversely of the receptacle cover door 4, and as is shown in Figure 4 the receptacle may be provided 85 with a series of transverse partitions 117 to form a series of compartments 118 in each of which a group of brushes extends. This division of the receptacle 110 is provided so that the various pieces of silverware 90 may be assorted, as for example knives may be all placed in one compartment, forks in another, teaspoons in the third and table spoons in the fourth. Passageways 119 are formed through the partitions so that the 95 water in the receptacle can freely circulate.

Having thus described my invention what I claim is:

1. In a dishwasher, a plurality of pairs of aligned plate receiving receptacles, a rotary 100 dish brush in each receptacle, a crank element connecting the brushes in each pair of receptacles, a shaft having operative connection with said cranks for simultaneously rotating the brushes, and resilient means in 105 each receptacle designed to support a plate in position to be acted upon by the adjacent brush.

2. In a dish washer, a plate receiving receptacle, a rotary dish cleaning brush 110 mounted within said receptacle, means for rotating said brush and a plate holding means adapted to support a plate in engagement with the brush comprising a wire frame structure having an edge portion 115 thereof extending inwardly to constitute a centrally located positioning ring, a cushion-pad supported by said ring and adapted to hold a dish in engagement with said brush, said wire frame structure constituting a resilient supporting means.

3. A dish washer comprising a dish receiving receptacle, a brush mounted therein, a split wire ring supported within said receptacle and spaced from said brush, said ring provided with a plurality of substantially parallel ends, means for receiving the ends and constituting a support therefor, said ring provided with portions bent outwardly from the plane thereof to constitute 130

a ledge for supporting the edge of a plate, a portion of the ring being bent inwardly toward the center thereof, and a pad supported by the inwardly extending portion of the 5 ring.

In testimony whereof I affix my signature.

BERNARD F. LUNDELL.
